BENJAMIN E. GETZ, OF MORTON, ILLINOIS

LAUNDRY APPARATUS

Substitute for application Serial No. 178,187, filed March 25, 1927. This application filed November 17, 1927.
Serial No. 234,020.

This invention has reference to improvements in laundry apparatus and particularly to that character of machine having a centrifugal drier, and the principal object of the 5 invention is to improve the construction of such drier.

One of the objects of the present invention is to provide the drier with a rotatable extracting member, and to rotate such member 10 within a revolvable casing, the latter having a housing, at its upper end, surrounding the extracting member and adapted to receive water expelled therefrom during the drying operation; said housing having a removable 15 lid or cover, forming when in open position a shelf over which materials may be passed to and from said drier and serving as a drain board to direct water from said housing to a tub or other receptacle and to catch drippings 20 from materials passed thereover.

The invention has for a further object to provide for the centrifugal extracting member, a casing supported to be revolved about said member and having connected thereto a 25 housing adapted to receive water expelled from said member; said housing adapted to be manually and circumferentially rotated to different positions and with it said casing; a cover hinged to said housing including a 30 locking means and supporting a rotatable member forming a closure for said extracting member; said hinged cover swingable to downwardly inclined positions, whereby it is capable of being used as a drain board to 35 direct water from said housing to a tub or other receptacle.

A further object of the invention is to provide a casing for the revolvable extracting member having a housing at its upper 40 end to receive water expelled from said member, and said casing and housing supported so as to be manually and circumferentially adjusted about said member; means being provided to automatically lock said casing 45 and housing against the torque during the rotation of said member; the casing and housing being capable of circumferential adjustment about said member in a direction opposite to the direction of rotation of said 50 member.

A still further object of the invention is to provide a centrifugal extractor with a housing adapted to be manually and circumferentially adjusted about its upper end; said housing having a hinged cover or lid supported so as to provide a closure for the housing and movable to a downwardly and inclined position to provide a shelf portion and drain board between said extractor and an adjoining tub or other receptacle. 55

Other and further objects will appear 60 from the following description.

That the invention may be more fully understood, reference is had to the accompanying drawings forming part of the description, 65 illustrating a preferred embodiment of the invention, in which:—

Fig. 1 is a plan view of machine, on a greatly reduced scale, showing a drier embodying my invention; 70

Fig. 2 is an elevation of what is shown in Fig. 1;

Fig. 3 is a vertical sectional view, on a somewhat larger scale, illustrating the interior construction of such drier, the cover 75 or lid for the housing being shown in open position;

Fig. 4 is a plan view, in section, as the same would appear on the line 4—4, Fig. 3;

Fig. 5 is a detail in section, as the same 80 would appear if taken on the line 5—5, Fig. 4;

Fig. 6 is a detail in elevation showing the hinge construction for the cover or lid for the housing, and 85

Fig. 7 is a detail sectional view showing the water discharge spout in the housing arranged for the discharge flow in a downwardly direction therefrom.

Like characters of reference denote corresponding parts throughout the figures. 90

Figs. 1, 2 and 3 show the centrifugal extractor associated with a washing tub A, the same having a suitable agitator a operated from a shaft b passing up through the bottom of the tub; the two such mechanisms supported in and by a suitable frame structure B, and in dotted lines in Figs. 1 and 2, I have shown a blueing or rinsing tub C. It being understood materials taken from the 100

tub A are placed in the centrifugal extractor for drying and may be removed therefrom into the tub C, the head and casing of the extractor being manually adjustable circumferentially thereof to position its drain board to provide a shelf over which materials are passed to and from said extractor and to catch any drippings from any such materials.

The drier, designated 1 is operatively supported in a vertical position in the frame B, alongside the tub A, providing thereby a unitary structure. The frame structure B, includes a head frame 2 having an upstanding annular bearing ring 3 and a connecting table 4 with the tub A, preferably inclined to the tub A, as shown in Fig. 3.

The drier 1 is supported on a gear housing or casing 5, within and on the frame B and which encloses gearing 6 adapted to receive its power from an operating shaft 7, said shafts 7 and b adapted to receive their power from any suitable source, such as an electric motor, not shown, whereby these two mechanisms may be operated simultaneously or separately. Said housing or casing 5 is preferably provided with an annular ring-like plate 8 through which extends an upstanding shaft 9 operatively connected with the gearing 6, preferably through clutch means 10.

Revolvably supported on the ring-like plate 8 is a casting 11 to which is connected and upstands an inverted cone-like casing 12 and the base of said casting 11 is flanged, as at 13, adapted in assembling to be revolvably held on the plate 8 by means of the cleats 14. The upper end of the casing 12 normally extends up into the bearing ring 3 and has connected thereto and supports an annular housing 15 having a shouldered portion 16 lying within and on the bearing ring 3, see Fig. 3, and adapted to be manually and circumferentially adjusted thereon. This housing has an enlarged annular opening 16' in its top wall for the insertion and removal of the revoluble extracting member 17, corresponding in shape to the casing 12 and preferably spaced therefrom, and its upper end, when in normal operative position, extending well up into the housing 15 above the upper end of the casing 12, its upper edge inturned, as at 18 to provide a guard, with its outer surface curved inwardly and downwardly, and with underlying water exit openings 19 through which water expelled from the extracting member 17 passes into the housing 15. A water shed, in the form of a ring-like member 20 is connected to and surrounds the extracting member 17 and overlies the upper end of the casing 12 and preferably a short upstanding flange 21 of the lower wall of the housing 15, whereby to direct water emitted from the openings 19 into the housing 15 and to prevent water entering down into the casing 12 between it and the

member 17. Said housing has a water discharge outlet 22.

To support and connect the centrifugal extracting member 17 to the shaft 9, I provide the shaft with an upstanding enclosing casing 23 connected at its lower end with the casting 11 by a suitable water seal 24, the shaft protruding through the upper end of said casing. The extracting member has connected thereto the axially arranged upstanding sleeve 25 adapted to have a telescopic connection and relation with the casing 23 and shouldered interiorly at its upper end to seat the upper end of said casing and is provided exteriorly with a seat 26 to receive a lug 27 on a knob 28 adapted to have connection with the shaft 9, whereby the centrifugal extracting member 17 may be caused to rotate with the said shaft 9 when power is applied thereto. Declutching of the extracting member from the power is accomplished by an attendant grasping the knob 28 and lifting it and the shaft 9.

The extracting member 17 with its ring-like member 20 is rotatable within the outer casing 12 and is replaceable in and removable from said casing 12 through the opening 16 in the housing 15, as it is believed will be understood. Also it is believed it will be understood that normally the casing 12 and the housing 15 are in non-rotation, while at the same time the extracting member 17 is revoluble therein, and that said housing 15 and with it said casing 12 may be manually and circumferentially adjusted about said extracting member 17 whether or not it is being revolved.

A cover or lid 29 is provided to close the opening 16 of the housing 15, and said cover or lid is preferably hinged to the housing, whereby it may be swung into a downwardly and inclined position so as to function as a shelf member between the drier and the tub A or the tub C or other receptacle over which materials are passed to and from said drier, and which also functions as a drain board to conduct water from the housing 15 passing out of the discharge 22 and to receive drippings from the materials passed thereover. I prefer to provide a two point hinge for said cover 29, comprising link members 30 which are pivoted at opposite points 31 to said housing 15 and said links at their upper and opposite ends pivoted to the cover, as at 32. To open the cover it is first swung on the pivots 32 and then swung bodily with the links 30 on their pivots 31 permitting the cover to be swung into the downwardly inclined position shown in full lines in Fig. 3 and in dotted lines in Fig. 1. The hinged side or end of the cover 29 is formed with a downwardly turned lip 33 adapted, when the cover is in opened position to lie under and engage the under side of the housing 15, as shown in Fig. 3, so as to act as a stop to hold

the cover in its properly inclined and open position.

The cover 15 supports a revoluble closure plate 34 adapted when the cover or lid 29 is closed, to rest on and engage the upper curved portion 18 of the member 17 to close said member, and when in such position the cover or lid 29 may be secured in closed position by means of the cam lever 35 pivoted to the top 10 of the housing 15. The closure plate 34 is preferably rotatably carried by the cover or lid 29 by a stem 35' and a ball bearing connection 36, see Fig. 3, the same being housed within a casing 37 formed on or connected to 15 the cover or lid 29. Such ball bearing connection between the centering plate 34 and said cover or lid 29 permits of a flexing of said centering member to adapt it to effectively engage the plate 20 so as to close said 20 member 17 and rotate therewith.

I provide an automatic locking means for the casting 11 and the casing 12 on the plate 8 whereby to lock said casing 12 against the torque when the shaft 9 and the extracting 25 member 17 are revolved. It being understood that the circumferential adjustment of the housing 15 and the casing 12 is in a direction opposite to the rotation of said shaft 9 and said extracting member 17. Such locking 30 means comprises the locking balls 38, see Figs. 3, 4 and 5 acting in tapered or inclined slots 39 in the casting 11, and functioning in a manner well understood. Such locking means is effective to hold the casing 12 against 35 the torque set up during and by reason of the rotation of the shaft 9 and will prevent the accidental rotation of said casing 12 and housing 15 under any and all conditions.

The casing 12 may or may not be provided 40 with the drain opening 40 at its lower end adapted to be controlled by a valve means 41 to which a pipe or hose, not shown, may be connected.

Fig. 7 shows the discharge opening 22 arranged in the bottom of the housing instead of in its side wall, as previously explained. With the same arrangement of the vertical and bodily movement of the cover or lid 29 it may still be positioned, as before described, 50 and receive the water discharged in a downwardly and vertical direction from said housing.

This application is a substitute for the application filed by applicant on the 25th day 55 of March, 1927, bearing Serial No. 178,187.

What I claim is:—

1. In combination, a centrifugal extracting member, a casing for said member and a housing connected with said casing and arranged to receive water expelled from said member, said housing and casing adapted for manual and circumferential adjustment about said member, and a drain board connected with 60 said housing and movable therewith whereby

to selectively discharge water at different points about said extracting member.

2. In combination, a centrifugal extracting member, a casing for said member, a housing connected with said casing and arranged to receive water expelled from said member, 70 said housing and casing adapted for manual and circumferential adjustment about said member, a cover for said housing adapted for service as a drain board and movable with the housing whereby to selectively discharge water at different points about said extracting member, and means to support said cover in an inclined position in different positions of said housing.

3. In combination, a centrifugal extracting member, means to revolve said member, a casing for said member, a housing connected with said casing and arranged to receive water expelled from said member, said housing 75 and casing adapted for manual and circumferential adjustment about said member, and means to automatically lock said casing against the torque due to the rotation of said member and its operating means.

4. In combination, a centrifugal extracting member, a casing for said member, a drain member connected thereto and arranged to be disposed in different positions to receive and direct water from said member, 80 said casing and said drain member adapted for manual and circumferential adjustment about said member, and means to automatically lock said casing against the torque due to the rotation of said member.

5. In combination, a support having a bearing ring, a centrifugal extractor member arranged within said ring, means to revolve said extractor, a casing for said member, means to revolvably support said casing, a housing connected with said casing and arranged to receive water expelled from said member, said housing and casing adapted for manual and circumferential adjustment about said member, and means to automatically lock said casing against the torque due to the rotation of said member and its operating means.

6. In combination, a centrifugal extracting member, a casing for said member revolvably supported at its lower end, means passing up through the lower end of said casing for revolving said member, a housing connected to said casing and revolvably supported about the upper end of said member 110 and arranged to receive water expelled from said member, said housing and casing adapted for manual and circumferential adjustment about said member, a cover hingedly connected with said housing and adapted to act as a drain board in different positions of said housing, and means to support said cover in an inclined position when opened.

7. In combination, a centrifugal extracting member, a casing for said member re- 120

volvably supported at its lower end, means passing up through the lower end of said casing for revolving said member, a housing connected to said casing and revolvably supported about the upper end of said member and arranged to receive water expelled from said member, said housing and casing adapted for manual and circumferential adjustment about said member, a cover hinged 5 to said housing and adapted to act as a drain board in different positions of said housing, means to support said cover in an inclined position when opened, and means to automatically lock said casing on its support against the torque due to the rotation of said member and its operating means.

8. In combination, a centrifugal extracting member having an upper bearing surface, means to revolve said member, a casing 20 for said member supported to be rotated, a housing connected with said member, a bearing support for said housing, said housing and casing adapted for manual and circumferential adjustment about said member, a cover for said housing, a member revolvably connected with said cover and arranged to engage the bearing surface of said member and to form a closure therefor and to rotate therewith, and means to support said cover in 25 a downwardly inclined position in relation to said housing.

9. In combination, a centrifugal extracting member having an upper bearing surface, means to revolve said member, a casing 35 for said member supported to be rotated, a housing connected with said member, a bearing support for said housing, said housing and casing adapted for manual and circumferential adjustment about said member, a cover for said housing, a member revolvably connected with said cover and arranged to engage the bearing surface of said member and to form a closure therefor and to rotate therewith, means to support said cover in a 40 downwardly inclined position in relation to said housing, and means to automatically lock said casing on its support against the torque due to the rotation of said member and its operating means.

10. In combination with a centrifugal extractor, a housing adapted to receive water expelled from said extractor and supported to be manually and circumferentially adjusted about said extractor, a cover connected to 55 said housing to adapt it to be bodily removed into an inclined position in relation to said housing and provided with a stop member to engage said housing and to determine its inclination in relation to said housing.

11. In combination with a centrifugal extractor, a housing adapted to receive water expelled from said extractor and supported to be manually and circumferentially adjusted about said extractor, a cover for said support, and hinged means for said cover includ-

ing links pivoted to said housing and to which said cover is also hinged, whereby said cover may be moved bodily from said housing and supported in a downwardly inclined position in relation to said housing.

12. In combination, a centrifugal extracting member, means to revolve said member, a casing for said member, a housing connected with said casing and arranged to receive water expelled from said member, said housing and casing adapted for manual and circumferential adjustment about said member, and means to lock said casing against the torque due to the rotation of said member and its operating means.

13. In combination, a centrifugal extracting member, means to revolve said member, a casing for said member, a housing connected with said casing and arranged to receive water expelled from said member, said housing and casing adapted for manual and circumferential adjustment about said member, and means to automatically lock said housing against the torque due to the rotation of said member and its operating means.

14. In combination, a centrifugal extracting member, a housing supported to be manually and circumferentially adjusted about said member, and a drain member having an adjustable pivotal connection with said housing, whereby it may be moved into different positions in relation to said housing.

15. In combination, a centrifugal extracting member, and a housing manually and circumferentially movable about said member and provided with a downwardly directed water discharge outlet, and a drain member adjustably connected with said housing and movable vertically into draining position, whereby to receive the discharge from said outlet in different positions of said housing and to selectively discharge water from and at different points about said extracting member.

In witness whereof, I have hereunto affixed my hand this 15th day of November, 1927.

BENJAMIN E. GETZ.
